UNITED STATES PATENT OFFICE.

MARTIN M. GARRISON, OF SYRACUSE, NEW YORK.

DESIGN FOR A BICYCLE-SADDLE.

SPECIFICATION forming part of Design No. 25,620, dated June 9, 1896.

Application filed April 22, 1896. Serial No. 588,647. Term of patent 7 years.

To all whom it may concern:

Be it known that I, MARTIN M. GARRISON, a citizen of the United States, residing at Syracuse, in the county of Onondaga, in the State 5 of New York, have invented a certain new and original Design for Bicycle-Saddles, of which the following, taken in connection with the accompanying drawings, is a full, clear, and exact description.

- 10 In said drawings, Figure 1 is a plan view of a bicycle-saddle, showing my design; and Fig. 2 is an end view of the same.

The leading features of my design consist in the general outline of the saddle, the front 15 of which is formed with the two curved borders $a\ a$, deflected with their main or central portions rearward, as shown at $a'\ a'$, and having their adjacent end portions $a^2\ a^2$ curved reverse from the central portions and meeting at the longitudinal central line b . The 20 outer ends $c\ c$ of said borders are also curved reverse from the central portions thereof and meet the borders $d\ d$ at the sides of the saddle.

These side borders extend for some distance approximately straight and slightly convergent rearward from the aforesaid ends $c\ c$ of the front border, as shown at $d'\ d'$, and thence continue with gradual inward curves $e\ e$ toward the central line b , where they meet and are formed with short forward curves $e'\ e'$. The two halves A A of the saddle are united along the central line b , where each of said halves is formed with a border f . All of said borders are sloped outward and downward and slightly convexed, as shown at $h\ h$ in Fig. 2 of the drawings.

What I claim is—

The design for a bicycle-saddle substantially as herein shown.

In testimony whereof I have heretounto signed my name this 13th day of April, 1896.

MARTIN M. GARRISON. [L. S.]
